UNITED STATES PATENT OFFICE.

CHARLES F. KETTERING, OF DAYTON, OHIO, ASSIGNOR, BY MESNE ASSIGNMENTS, TO DELCO-LIGHT COMPANY, OF DAYTON, OHIO, A CORPORATION OF DELAWARE.

PROTECTING DEVICE.

Application filed March 26, 1917. Serial No. 157,442.

To all whom it may concern:

Be it known that I, CHARLES F. KETTERING, a citizen of the United States of America, residing at Dayton, in the county of 5 Montgomery and State of Ohio, have invented certain new and useful Improvements in Protecting Devices, of which the following is a full, clear, and exact description.

This invention relates to improvements in 10 guards for the moving elements of machines of various types.

One of the objects of the present invention is to provide a guard for the moving elements of machinery which will effectually 15 prevent the moving parts of the machine from causing injury to the attendants or operators of the machine, without interfering with the functioning of these parts in any way.

20 A further object of the present invention is to provide a guard particularly adapted to be combined with a moving element of a machine, such as a flywheel of an engine, which is so constructed as to function as 25 a fan, this guard being so combined with the flywheel that it will prevent injury and at the same time will tend to assist the functioning of the flywheel as a fan.

Further objects and advantages of the 30 present invention will be apparent from the following description, reference being had to the accompanying drawing wherein a preferred form of one embodiment of the present invention is clearly illustrated.

35 In the drawing:-

Fig. 1 is a view in side elevation of one form of the present invention, certain of the elements included in the present invention being shown in section for the sake of 40 clearness.

Fig. 2 is a view in end elevation of the guard removed from the flywheel, a portion of said guard being shown in section to 45 more clearly illustrate the construction thereof.

Referring to the drawing, and more particularly to Fig. 1 thereof, it will be noted that the present invention is shown combined with a power unit including a gas engine 50 and a dynamo-electric-machine, such as is described, illustrated and claimed in the patent to Charles F. Kettering and William A. Chryst, No. 1,341,327, dated May 25, 1920. It will be understood, however, that this is

not intended as a limitation, but is simply 55 selected for purposes of illustration.

The numeral 20 indicates the engine of the above mentioned power unit, and this particular type of engine is of the air-cooled type, being provided with a casing 21 spaced apart from the engine cylinder 22, said casing having a communicating opening with the flywheel chamber 23. The flywheel 24, which is mounted in the usual manner upon the crank shaft of the engine, not only functions as a balance wheel but is provided with a series of peripheral blades 25, which, combined with certain radial blades not shown in the present drawing, permit this flywheel to function as a fan and suck 70 air down through the space between the engine cylinder 22 and the casing 21. The air, which is drawn through the above mentioned space, tends to act as a cooling agent relative to the engine and is discharged by 75 the flywheel after it has performed its cooling function.

It will be apparent, however, that a flywheel of this type, which is provided with peripheral openings and peripheral blades, 80 may cause injury to the attendant or operator of the engine, and it is therefore one of the objects of the present invention to provide an enveloping guard which will effectually prevent the attendant from being 85 injured by coming in contact with any portion of the flywheel and at the same time will not interfere with the functioning of the flywheel either as a fan or as a balance wheel. This guard is designated by the 90 numeral 26 and comprises a casing including an end plate 27 and a cylindrical portion 28 which is adapted to surround the tread or periphery of the flywheel. In order to effectually inclose the flywheel, the 95 extremity of the cylindrical portion 28 is bent inwardly as at 29 and lies adjacent to the inner portion 30 of the flywheel 24.

From the above description it will be apparent that this guard forms a casing about 10 the flywheel and will effectually prevent anyone from coming in contact inadvertently with the flywheel.

In order to permit the discharge of the air by the flywheel functioning as a fan, the cylindrical portion 28 of the guard is provided with a series of openings 31 which lie in direct alinement with the peripheral

blades of the flywheel and the openings therebetween. In order to assist in the discharge of the air through these openings 31, a deflecting or ejector plate or blade 32 is secured to the cylindrical portion of the guard adjacent to each of the openings 31. The free end of each of these ejector blades 32 lies in close proximity to the peripheral blades of the flywheel and assists in the rapid discharge of the air which is forced out by the flywheel functioning as a fan.

It will be noted, however, from the showing in Fig. 2 that these deflector blades are so arranged that it is substantially impossible for any object to be inserted through the openings 31 into contact with the flywheel. In order to provide for a firm mounting of the guard relative to the flywheel, a pair of supporting feet 33 are secured to the guard 20 as at 34, and are adapted to be secured either to the base 35 of the engine or to an adjacent support.

In Fig. 2 of the drawing, the ejector blades or plates 32 are shown as being integrally secured to the cylindrical portion of the guard. In this particular form of the invention, the guard is punched or cut away on three sides and the cut-away portion of the guard is then depressed and so formed as to provide the ejector blades as shown in Fig. 2. It will be apparent, however, that these blades may be readily replaced with an independent plate which can be secured to the cylindrical portion of the 35 casing in any desired manner.

The arrow 34 in Fig. 2 indicates the direction of rotation of the flywheel, and consequently the direction in which the air is discharged by the flywheel functioning as 40 a fan. It will of course be understood that the angle at which the ejector blades are positioned or headed into the current of discharging air is such as will give the greatest efficiency, and as will offer the least resistance to the normal flow of the current of air discharging through the ventilating openings of the guard.

While the form of mechanism herein shown and described constitutes a preferred 50 embodiment of one form of the invention, it is to be understood that other forms might be adopted, and various changes and alterations made in the shape, size, and proportions of the elements therein without departing from the spirit and scope of the invention.

What I claim is as follows:

1. In a device of the character described, the combination with a rotating element 60 having a periphery adapted to function as a fan and having peripheral blades; of a guard for said rotating element including an end plate having a cylindrical portion adapted to lie concentric with the periphery of the moving element, said cylindrical

portion being provided with ventilating openings and having ejector blades secured to said portion and extended toward the periphery of the rotating element.

2. In a device of the character described, 70 the combination with a flywheel having peripheral fan blades which will enable said flywheel to function as a fan; of a guard including an end portion and a cylindrical portion, said flywheel lying concentric relative to said cylindrical portion, said cylindrical portion being provided with a plurality of openings directly in alignment with the peripheral fan blades of the flywheel.

3. In a device of the character described, 80 the combination with a flywheel having fan blades which will enable said flywheel to function as a fan; of guard means including side and peripheral portions for enclosing said flywheel, one of said portions 85 being provided with a plurality of openings in the direct path of the air currents and arranged to permit the passage of said air currents freely and without substantial deflection.

4. In a device of the character described, the combination with a flywheel having fan blades which will enable said flywheel to function as a fan; of guard means having a portion adjacent said flywheel provided with a plurality of openings in the direct path of the air currents and having inwardly extending blades adjacent said openings, said openings and blades being arranged to permit the passage of said air 100 currents freely and without substantial deflection.

5. In a guard for fan elements of machines, the combination with a fan element having fan blades; of a guard for said fan element comprising a hollow cylinder closed at one end and open at the other and arranged concentrically with respect to the fan, and having its cylindrical wall provided with openings in substantial alignment with the fan blades, and having its open end constructed and arranged so as to permit withdrawal of the guard from the fan.

6. A guard for movable elements which agitate the air into currents, comprising an enveloping guard portion having ventilating openings therein; and blades adjacent the openings and substantially parallel with the direction of flow of the air currents.

7. A guard for rotary elements which agitate the air centrifugally into currents, comprising an enveloping guard portion having ventilating openings therein about the periphery of the rotary element; and blades adjacent the openings and substantially parallel with the direction of flow of the air currents.

8. In a guard for fan elements of ma-

chines, the combination with a centrifugal fan element for discharging air currents; of an enveloping guard portion around the fan element, the guard portion being provided with ventilating openings therein in the direct path of the discharging air currents, whereby the discharge of the air currents will be in the plane of the fan element.

10 9. In a device of the character described, in combination, an engine having a crank case and a crank shaft; engine cooling means including a flywheel fan mounted on the crank shaft adjacent said crank case; and means cooperating with said crank case to house said flywheel fan, said means having openings therein in the direct path of the air currents from said flywheel fan and arranged to permit the free passage of air currents therefrom.

10 10. In a device of the character described, in combination, an engine having a crank case and a crank shaft; engine cooling means a flywheel mounted on the crank shaft adjacent the crank case and having peripheral fan blades; and means carried by the engine and cooperating with the crank case adapted to house said flywheel, said means having openings in the direct path of the air currents from said fan blades and arranged to permit the passage of said air currents freely and without substantial deflection.

11. In a device of the character described, in combination, an engine having a crank case and a crank shaft; engine cooling means including a peripheral discharge fan mounted on the crank shaft; and means cooperating with said crank case to house said flywheel fan, said means having openings therein in the direct path of the air currents discharged from the fan whereby the discharge of the air currents will be in the plane of the fan element.

12. In a device of the class described and in combination with an engine having a crank shaft, engine cooling means including a casing supported by the engine and surrounding the cylinder thereof; a fly wheel fan mounted on the crank shaft adjacent the engine and adapted to induce a flow of air through said casing, and to discharge the same into the surrounding atmosphere; and means cooperating with the engine to house said fly wheel fan, said means having openings therein to direct the air currents from said fly wheel fan and permit the free passage of air therefrom.

In testimony whereof I affix my signature in the presence of two subscribing witnesses.

CHARLES F. KETTERING.
